UNITED STATES PATENT OFFICE.

WILLIAM R. JEAVONS, OF CLEVELAND, OHIO.

DESIGN FOR A STOVE-BASE.

45,532.

Specification for Design.

Patented Mar. 31, 1914.

Application filed November 6, 1913. Serial No. 799,622. Term of patent 14 years.

To all whom it may concern:

Be it known that I, WILLIAM R. JEAVONS, a citizen of the United States, residing at Cleveland, in the county of Cuyahoga and State of Ohio, have invented a new, original, and ornamental Design for Stove-Bases, of which the following is a specification, reference being had to the accompanying drawing, forming part thereof, wherein the figure

illustrates in elevation a stove-base, showing my new design.

I claim:—

The ornamental design for a stove base, as shown.

WILLIAM R. JEAVONS.

Witnesses:

BRENNAN B. WEST,
J. B. HULL.
